UNITED STATES PATENT OFFICE.

JAMES M. IDE, OF TROY, NEW YORK, ASSIGNOR TO GEORGE P. IDE & CO.,
OF SAME PLACE.

DESIGN FOR A COLLAR.

SPECIFICATION forming part of Design No. 18,699, dated October 23, 1883.

Application filed July 23, 1888. Serial No. 280,828. Term of patent 7 years.

To all whom it may concern:

Be it known that I, JAMES M. IDE, of the city of Troy, county of Rensselaer, State of New York, have invented a new and useful Design 5 for Apparel-Collars for Female Wear, of which the following is a specification.

My invention relates to a design for an apparel-collar for female wear, and the same is shown in the accompanying drawings, forming a part of this specification, in which drawings—

Figure 1 shows a plan view of the collar laid out flat, and Fig. 2 shows a perspective of the same collar with the ends connected as when 15 worn.

The parts of the collar thus illustrated are designated by letter reference and described as follows:

The letter C designates the collar proper, it 20 being shown as having downwardly and outwardly tapering ends e and angular top corners a, although, if desired, these corners may be rounded off, as indicated by the dotted lines d, without changing my design.

The letters K designate cape-form tabs arranged on the lower edge of the collar at each end, and the letters T designate tab-form cape parts that are downwardly projected from the lower edge of the collar proper between the 25 end tab-form parts K.

The tab-form parts K have straight front edges and rounded inner edges, and are nar-

rower where uniting with the bottom of the collar proper than where downwardly extended therefrom.

The tab-form cape parts T have rounded lower ends and taper upwardly and inwardly on their side edges to where they attach to the bottom of the collar proper, so as to leave the uncaped parts s upon the bottom of the collar proper.

This design for a collar is distinguished by three of the tab-form cape parts arranged upon the lower edge of the collar proper between the end tab-form cape parts, K.

Having thus described my design for an apparel-collar for female wear, what I claim, and desire to secure by Letters Patent, is—

The design for an apparel-collar, consisting of the collar proper, C, having the end cape parts, K, with straight front edges and rounded and inwardly tapering side edges, and the tab-form cape parts T, having rounded bottom edges and inwardly and upwardly tapering side edges arranged upon the lower edge of the collar proper, so as to leave the uncaped spaces s, as shown and described.

Signed at Troy, New York, this 23d day of April, 1888, in the presence of the two witnesses whose names are hereto written.

JAMES M. IDE.
